UNITED STATES PATENT OFFICE.

RICHARD W. BURNETT, OF CHICAGO, ILLINOIS.

CAR-ROOF.

1,360,092.

Specification of Letters Patent. Patented Nov. 23, 1920.

Application filed September 20, 1917. Serial No. 192,324.

To all whom it may concern:

Be it known that I, RICHARD W. BURNETT, a citizen of the United States of America, residing at Chicago, in the county of Cook 5 and State of Illinois, have invented certain new and useful Improvements in Car-Roofs, of which the following is a specification, reference being had therein to the accompanying drawing.

10 The invention relates to car-roofs of that type in which the roofing sheets are arranged beneath channel carlines and are provided with nested flanges within the channels of the carlines, forming in connection therewith weather-proofing means. The present invention comprises the novel construction of flanges by which more thorough weather-proofing is obtained, and further certain features of construction as 15 hereinafter set forth.

In the drawings:

Figure 1 is a sectional side elevation through the roof;

25 Figs. 2 and 3 are similar views showing modified constructions; and

Fig. 4 is a cross-section through the car-roof substantially in the plane 4—4 Fig. 1.

In the construction of roofs of the type above referred to it is usual to provide the 30 adjacent upstanding flanges of the roofing sheets with oppositely returnbent portions nested together and supported upon saddles or bearing blocks suspended from the carline. The weather-proofing is effected, first, 35 by the inverted channel carline which forms a cap for the nested flanges; and second, by the nested flanges themselves. Thus any water that may pass between the carline and the sheet must rise above the flanges to find 40 access to the interior of the car. However, under certain conditions of strong wind pressure, water blown in the crevice beneath the carline may mount the underlapping flange and be forced between the same and the overlapping flange to the interior of the 45 car. With my improved construction this effect is impossible, for the reason that the underlapping flange is turned in the same direction as the overlapping flange, and any 50 water mounting either of the flanges will be deflected outward or away from the joint. I have also devised an improved means of supporting the roofing sheets and for limiting the movement thereof to prevent disengagement, the specific construction being as 55 follows:

A is a carline of inverted channel or U-shaped cross-section, having the outwardly-extending flanges B, and C are roofing sheets extending from eaves to eaves 60 and provided on their opposite edges with upstanding flanges D arranged within the channels of the carlines. The adjacent upstanding flanges of adjacent sheets are formed with returnbent portions E and E'. 65 The flange E extends laterally outward or away from the body of the sheet, while the flange E' extends laterally inward or toward the body of the sheet, and thus when the two flanges are nested the upstanding flanges 70 from which they spring will be in proximity, while the free end of the returnbends will be also adjacent. This will cause any water blown along the sheet and up the flange thereof to be deflected away from the joint 75 instead of being forced thereinto.

For supporting the sheets I preferably provide a ledge or bracket F projecting from the inner face of the carline, upon which the returnbend of the sheet may rest. In 80 Figs. 1 and 3 this ledge is shown as an angle bracket secured to the carline and projecting inward therefrom, the inner end being curved or inclined downward to facilitate mounting the returnbends of the sheets 85 thereon. Displacement of the sheets from this support may be prevented by the depending eaves flanges G, which are apertured for the passage of the bolts H securing the carline to the side-plate of the car. The 90 apertures I in these eaves flanges are larger than the bolts passing therethrough so as to provide a limited freedom of movement to the sheets to compensate for the weaving and flexing of the car, but any movement sufficient to disengage the returnbends from the ledge F will be prevented. Another 95 means of accomplishing the same result is the placing of a stop on the opposite side of the flanges from the ledge F to limit the movement thereof. Such a construction is shown in Fig. 1, in which J is a stop member, preferably struck inward from the metal of the carline adjacent to the neutral axis. This will not materially weaken the carline, as the metal which is removed is not in work and the projecting inner end will form a limiting stop for the flanges. 100

Where the sheets are made of metal of sufficient gage, they may derive sufficient 110 support from the trussing effect of the upstanding flange and returnbend, and without

the addition of any other supporting means. Such a construction is shown in Fig. 2, and, as shown in Fig. 4, the radius of the carline longitudinally thereof or transversely of the car is different from that of the sheet so as to exert a downward pressure thereon at the center, placing the metal under tension.

What I claim as my invention is:

1. In a car roof, the combination with an inverted channel carline, of roofing sheets arranged therebeneath and having upstanding flanges adjacent to each other, the upper portions of said flanges being returnbent in the same direction and nested, and a shelf 10 within said carline engaging the edge of the returnbent flange to form a support for the sheet.
2. In a car roof, the combination with an inverted channel carline, of roofing sheets arranged therebeneath and having upstanding flanges centrally of the channel, returnbent in the same direction and nested, the free ends of said returnbends being adjacent to the side of the channel, a shelf or support 20 within said carline for engaging the free edge of said returnbent flange, and a stop for limiting the movement of said sheets 25

to maintain said returnbent flange in engagement with said support.

3. In a car roof, the combination with an inverted channel carline, of roofing sheets arranged therebeneath and having upstanding flanges centrally of the channel, said flanges terminating in portions returnbent in the same direction and nested, a shelf or support within said carline for engaging the free edge of a returnbent flange, and a stop struck inward from the opposite side of said carline for limiting movement of the sheets.

4. In a car roof, the combination with an inverted channel carline, of roofing sheets arranged therebeneath and having upstanding flanges adjacent to each other, the upper portions of said flanges being returnbent in the same direction and nested.

5. In a car roof, the combination with an inverted channel carline, of roofing sheets curved transversely of the roof, arranged beneath said carline and having upstanding flanges adjacent to each other, the upper portions of said flanges being returnbent in the same direction and nested.

In testimony whereof I affix my signature.

RICHARD W. BURNETT.
